SECTIONAL FUEL DISTRIBUTOR

Washington T. Capps, Baltimore, Md., assignor,
by mesne assignments, to Standard Stoker
Company, Inc., (1922), New York, N. Y., a cor-
poration of Delaware

Application April 10, 1935, Serial No. 15,517

1 Claim. (Cl. 110—101)

This invention relates to improvements in sectional fuel distributors used with stokers and particularly to fuel distributors of the general type shown in my prior United States Letters Patent 1,875,216, dated August 30, 1932.

In the form of locomotive stokers to which this invention is particularly applicable, it is important that the fuel distributor member which is exposed to the intense heat of the firebox may be readily removed from its operative relation with associated stoker parts whenever it becomes warped, or is otherwise made unfit for further service; at the same time, the fuel distributor member must be so related with associated stoker parts that its position within the firebox will be maintained without danger of accidental displacement or by reason of uneven running of the locomotive such as may occur while stopping and starting trains, and especially over a rough roadbed.

Accordingly, it is the principal object of this invention to provide an improved attachment or connecting relation between a fuel distributor member and associated stoker parts.

It is a further object of this invention to provide a novel attachment or connecting relation between the parts of a sectional fuel distributor comprising separable front and rear sections, this connecting relation in its specific embodiment including a portion at an adjacent end of each section underlying the other section, thereby restraining downward movement of one section relative to the other, and means for restraining relative fore and aft movement between said sections.

More specifically, it is the object of this invention to provide the novel attachment or connecting relation between the lower front fuel deflecting section and the rearward tubular element of a stoker fuel distributor member.

These and other objects and advantages will be apparent from the description of my invention and the accompanying drawing, wherein,

Fig. 1 is a vertical longitudinal sectional view of my improved stoker distributor with associated parts indicated by the dotted lines;

Fig. 2 is a side elevation of the stoker distributor according to my invention;

Fig. 3 is a sectional plan view of the structure shown in Fig. 2 taken on the line 3—3 thereof;

Fig. 4 is a sectional view taken on the line 4—4 of Fig. 2 looking in the direction of the arrows;

Fig. 5 is a sectional view taken on the line 5—5 of Fig. 2 looking in the direction of the arrows; and

Fig. 6 is a fragmentary sectional view taken on the line 6—6 of Fig. 2.

Throughout the description and claims, the terms "front" and "rear" and similar terms are used relative to the passage of fuel through the distributor.

On the drawing, 10 indicates a firebox comprising inner and outer sheets 11 and 12, respectively, and between which extends a thimble 13 constituting a stoker firing opening 14. At 15 10 is indicated a stoker conveyor which delivers fuel, such as coal, in front of the jet member 16. The jet member 16 is arranged to issue blasts of pressure fluid against the fuel so delivered for projecting it through the distributor member D over the fuel supporting surface 46 thereof.

The distributor member D is connected to the stoker conduit 15 by means of a T head bolt 17 and intermediate its ends is supported from the thimble 13 by means of cap screws 18 threaded 20 into the tubular element 19 of the stoker fuel distributor member. This tubular element 19 passes through the stoker firing opening 14 so that the forward end thereof is preferably within the firebox 10, and comprises the arcuate side 25 walls 20, 21 and the flat top and bottom walls 22, 23, respectively. Extending upwardly from the upper side of the top wall 22, and at the forward end thereof, is a lug 24 which is engaged between the spaced ears 25 formed at the rearward end of the upper fuel deflector 26 which functions to prevent the upper stratum of fuel, as it is blasted through the tubular element 19, from being drawn upwardly into the firebox and through the flues by the locomotive draft. A 30 pin 27 passing into the ears 25 and through the lug 24 prevents movement of said upper fuel deflector 26 in a forward direction with reference to said tubular element 19. At each side of the upper fuel deflector 26 a stop 28 is provided, each 35 stop contacting the forward edge 29 of a respective arcuate side wall 20, 21 for restraining downward swinging movement of the deflector 26 with reference to the tubular member 19. The deflector 26 at its upper side is adequately ribbed 40 as at 30 in order to prevent warping or sagging thereof due to the intense heat within the firebox.

The attachment or connecting relation between the tubular element 19 and the lower fuel 50 deflector 31 is a novel one and will now be described in detail. Considered broadly, the deflector 31 and the tubular element 19 are each a separable section or portion of a sectional distributor in which the tubular element or rear 55

section 19 is carried by the stoker conveyor 15 while the deflector 31 or front section, which is within the firebox and therefore must be frequently renewed, is carried by and supported 5 from the tubular element or rear section 19.

In detail, the aforesaid connecting relation 10 between the front and rear sections is attained by providing a recess 32 in the forward end of the bottom wall 23 of the tubular element 19; at 15 each side of the recess 32 and below the fuel supporting surface 46 of the distributor member D is a ledge 33 upon which is seated the rearward portion 34 of the distributor member 31. The distributor member 31 is formed so as to direct laterally fuel which is propelled in a generally forward direction by the jet member 16.

Centrally of the distributor member 31 and 20 depending from the under side thereof is the lug 35 which has a rearward extension 36 disposed below the upper surface of said rearward portion 34. The lug 35 is disposed between the ledges 33, and its rearward extension 36 fits between spaced flanges 37, 38 depending from the under side of the bottom wall 23 of the tubular 25 element 19. At their forward ends, the flanges 37, 38 merge into the ledges 33 and are connected at their rearward ends by a bridge wall 39, thereby assuring a firm construction which is not liable to warp or spread under the intense 30 firebox heat.

Thus, it will be apparent that the ledges 33 of the tubular element 19 underlie the rearward portion 34 of the distributor member 31 while the rearward extension 36 of the latter underlies 35 the bottom wall 23 of the former. Lateral movement of the distributor member 31 with reference to the tubular element 19 is restrained by reason of the lug 35 which fits closely between the inner sides of the ledges 33 and depending flanges 37, 40 38. Movement of the distributor member 31 in

a forward direction with reference to said tubular element is prevented by passing a pin 40 transversely of the distributor member D so that it passes into the ledges 33 and through the lug 35 below the fuel supporting surface 46. 5

From the foregoing description, it will be clear 10 that the distributor member 31 of my invention is held firmly by the tubular element 19 so that it cannot fall onto the firebed under severe locomotive operating conditions; at the same time, 15 the connection between the distributor member 31 and the tubular element 19 is such that upon removal of the pin 40 the member 31 may be removed from the tubular element 19 by a forward movement. 15

I claim:

In combination with a furnace having an upright wall provided with an opening therein, a stoker for feeding fuel to said furnace comprising a distributor member extending, from a point 20 rearward of said upright wall, through said opening to a point within said furnace, said distributor member having a fuel supporting surface arranged to permit fuel to pass thereover for distribution over a fire and comprising a rear section and a front section separable from said rear section, said rear section having a ledge disposed 25 forward of said upright wall and underlying said front section below the fuel supporting surface thereof, and a pair of spaced flanges depending 30 from the under side of said rear section, a lug formed with the under side of said front section and having a rearward extension, said lug and extension fitting between said spaced flanges, and said extension underlying said rear section, and 35 means beneath said ledge extending into said front and rear sections below their fuel supporting surfaces for restraining said sections against relative fore and aft movement.

WASHINGTON T. CAPPS. 40
